UNITED STATES PATENT OFFICE.

GEORGE C. GARDNER, OF CHICAGO, ILLINOIS.

DESIGN FOR A TRACK FOR DOOR-HANGERS.

SPECIFICATION forming part of Design No. 26,886, dated April 13, 1897.

Application filed February 20, 1897. Serial No. 624,484. Term of patent 7 years.

To all whom it may concern:

Be it known that I, GEORGE C. GARDNER, a citizen of the United States of America, residing at Chicago, in the county of Cook and State of Illinois, have invented a new and original Design for a Track for Door-Hangers, of which the following is a specification.

My invention relates to a new and original design for a track for door-hangers and the like and is illustrated in the accompanying drawings by means of two figures, of which—

Figure 1 is a face view or elevation of my design, and Fig. 2 is a section in line 2 2 of Fig. 1.

Referring to the drawings, the track will be seen to be of substantially even thickness and to be composed of a flat rear portion A, curved outward at the top and bottom a a' , said curves being continued until the opposite edges approach each other at a^2 a^3 , and

then joining reverse curves a^4 a^5 , from which extend outward substantially straight portions a^6 a^7 , terminating in curves a^8 a^9 , extending away from each other and completing the outline of the track. The longitudinal parallel elements of the track are preferably straight lines, although I consider this immaterial to my design, the essential features of which I believe to be the outward curves a a' , the return a^2 a^3 , and the reverse curves a^4 a^5 .

I claim as new and desire to secure by Letters Patent—

The design for a track for door-hangers; substantially as shown and described.

GEORGE C. GARDNER.
